WALTER ANDERSON, OF KILLINGLY, CONNECTICUT, ASSIGNOR TO ANDERSON MILL SUPPLY COMPANY, OF KILLINGLY, CONNECTICUT, A CORPORATION OF CONNECTICUT

LUG STRAP FOR LOOMS

Application filed June 8, 1928. Serial No. 283,865.

This invention relates to lug straps such as are used in connection with the picker sticks of weaving looms for throwing the shuttle from end to end of the batten, and has more particular reference to lug straps of that class having an integral reinforcing cushion of the fulcrum or roller type.

Lug straps of this class are ordinarily constructed of less width at and adjacent the bend than at the ends, the intermediate portion of the strap being upset or compressed edgewise to so reduce the width and to force the surplus material inwardly to form a reinforcing cushion having a curved surface adapted to give a roller motion when in contact with the picker stick. The cushions of these conventional lug straps, or the curved fulcrum surfaces thereof, extend from edge to edge of the straps at the bend. Experience has proven that in lug straps thus formed a weak place is had at each side of the strap where the narrow intermediate portion merges with the wider end portions. This weakness is objectionable especially in view of the fact that the cushion extends to the edges of the strap at the bend, causing the picker stick to come into constant active contact with the edges of the cushion so as to mutilate them and soon destroy the usefulness of the strap.

The primary object of the present invention, therefore, is to provide an improved lug strap of the class mentioned by means of which the above objections are effectively overcome without the aid of objectionable separate pads or facings, thereby insuring better results and longer life of the strap as compared with the straps of conventional form. I preferably accomplish this object by forming the lug strap of uniform width throughout, and by providing the same with an integral internal fulcrum cushion of slightly less width than the strap and of such depth that the picker stick may not contact or pound the edges of the strap at the bend.

In the accompanying drawing, wherein a preferred embodiment of the invention is shown,

Figure 1 is a fragmentary side elevational

view, showing the present lug strap operatively associated with the lug stick and the picker stick of a loom.

Figure 2 is a horizontal section on line 2—2 of Figure 1.

Figure 3 is a central vertical longitudinal section of the lug strap, detached; and

Figure 4 is a fragmentary vertical transverse section on line 4—4 of Figure 1.

Referring more in detail to the drawing, the present lug strap consists of an elongated strip 5 of suitable composite material, duck, leather or the like, return-bent into substantially U-shape as shown in Figure 2 and of uniform width throughout as shown in Figures 1 and 3, thus strengthening the strap at the bend where subjected to the greatest wear and where maximum strength is needed.

The strap is molded or otherwise suitably formed with an integral internal fulcrum cushion 6 of slightly less width than that of the strap so as to leave narrow flat surfaces or shoulders 7 between the edges of the cushion and the edges of the strap, and of such depth that the picker stick 8 may not contact or pound the edges of the strap at the bend. This insures perfect operation with no wear on the edges of the lug strap.

The bearing or impact surface of the cushion 6 is of the usual convex or curved form, and said cushion is preferably of such length to extend across the bend and part way along the sides of the lug strap, the ends of the cushion being arched as at 9. This gives the strap maximum strength and prevents breaking thereof at the sides.

The ends of the strap may be slotted in the usual way for being bolted as at 10 to the lug stick 11, and any suitable means may be provided for connecting the supporting loop 12 to the lug strap for holding the latter in proper relation to the picker stick.

I find in practice that the present lug strap gives better results and lasts longer than straps having the bend of less width than the ends and having the cushion of the same width as the strap at the bend, as now commonly made.

What I claim as new is:

In a loom having a picker stick a lug strap

of fibrous material bent to provide a looped portion and spaced arms all of which are of substantially the same width, an integral internal cushion formed on the inner faces of the looped portion and the respective arms, said cushion providing a convexed impact surface and being of uniform width throughout its length, the upper and lower edges of the cushion being spaced from the upper and lower edges of the strap to leave narrow flat surfaces between the edges of the cushion and strap respectively, thereby making it impossible for the picker stick to contact with or mutilate the edges of the cushion at the bend.

In testimony whereof I affix my signature.
WALTER ANDERSON.
